WINDOW OPERATOR

Matt Giupkaytis, Miami, Fla.

Application July 11, 1951, Serial No. 236,215

2 Claims. (Cl. 268—23)

1

This invention relates to window operators and more particularly to a novel and advantageous type of operator for windows of the so-called "awning" type comprising a vertical series of horizontally pivoted sash.

Windows of the awning type are coming into widespread use, particularly in warm climates where it is desirable to employ sash which may be opened to uncover the entire area of the window opening, as contrasted with the so-called "double hung" sash, which can uncover not more than half the area of the window opening at any time. Awning type windows have other advantages as compared with other types of windows, one of them being that the window operating linkage may be employed to counterbalance the several sash in the series, so that opening and closing movements of the window may be accomplished with little effort. Incident to this feature of awning type windows is the fact that they may be easily adapted for operation in the closing direction by the weight of rain water falling upon the sash and collected by suitable means carried by the individual sash, such an arrangement being described and claimed in United States Patent No. 2,528,953, granted November 7, 1950.

When awning type windows are adapted to be "rain-operated," there must, of course, be provision for disconnecting the operating linkage from the manual control or window operator, so that the sash may swing to closed position by gravity, regardless of the position of the manual control. A general object of the present invention is to provide an improved manual control, together with a novel and improved clutch for connecting and disconnecting the same relative to the vertically disposed operating linkage which connects the several sash.

Another object is the provision of a window operator for windows of the type described, employing a simple lever principle instead of the crank and worm gear operation heretofore employed in most cases, and which is needlessly expensive and cumbersome.

A further object is the provision, in a window operator of the character described, of simple and effective means for locking the operator in an adjusted position, whereby the sash are likewise locked in the adjusted position so long as the operating linkage and window operator are operatively connected.

Other and further objects, features and advantages will be apparent from the description which follows, read in connection with the accompanying drawings in which

Figure 1 is a front elevation of the lower portion

2

of a window provided with the present invention; Figure 2 is a side elevation of the device of Figure 1;

Figure 3 is a section on line 3—3 of Figure 1;

Figure 4 is a section on line 4—4 of Figure 3;

Figure 5 is a section on line 5—5 of Figure 3; and

Figure 6 is a fragmentary section on line 6—6 of Figure 3.

In order to facilitate an understanding of the invention, reference is made to the embodiment thereof shown in the accompanying drawings and detailed descriptive language is employed. It will nevertheless be understood that no limitation of the invention is thereby intended and that various changes and alterations are contemplated such as would ordinarily occur to one skilled in the art to which the invention relates.

The lower portion of an awning type window is illustrated in Figures 1 and 2, and comprises generally a rectangular window frame of which the sill 10 and vertical members 11 and 12 are shown, and in which are supported a vertical series of sash 13. Each sash 13 is mounted for angular movement about a horizontal axis at or near its upper edge, and is provided with a rearwardly and upwardly extending arm 14 at one side of the sash for connection to the operating linkage. The latter comprises a vertical series of links 15, the lowermost link in the series being pivotally connected at its upper end to the lowermost arm 14 and at its lower end to the manual control or window operator to be described. The window frame 10 is preferably of sheet metal construction and hollow, to receive the operating linkage just described, as well as to permit the window operator to be recessed thereinto.

The window operator is mounted on a supporting frame consisting of vertical side members 16, 17 rigidly secured through transverse members 18 and 19. For convenience, the side members 16 and 17 are shown as separate elements, although it will be readily understood that the supporting frame may be fabricated as part of a sheet metal window frame, vertically extending parallel elements of which may perform the function of side members 16 and 17. The frame is completed by the closure plate 20 having straight end portions and an arcuate intermediate portion 21 which is slotted substantially throughout its length as at 22.

A horizontal pivot pin 23 extends between the side members 16 and 17 substantially intermediate their ends and, for convenience in assembly, may have threaded connection therewith as illustrated in Figure 4. A lever 24, journalled on the pivot

pin 23 is pivotally connected at its distal end to the lower end of the lowermost link 15 and is provided with a tail portion 25 extending beyond the pivot pin 23 in the direction away from the link 15.

Also journalled on the pivot pin 23 is a part-cylindrical drum-like enclosure 26 comprising side walls 27, 28 and an arcuate wall 29 which makes sliding engagement with the closure plate 20 of the supporting frame. Fixed in the wall 29 of the enclosure 26 and extending outwardly through the slot 22 of the closure plate 20 is a radial stud 30 on which is threaded a handle 31. A spring washer 32 is preferably mounted on the stud 30 between the handle 31 and the closure plate 20.

A clutch member 33 comprises a rod 34 slidably mounted in a suitable aperture in the wall 29 of the enclosure 26, and a U-shaped yoke 35 secured on the inner end of said rod. The yoke is connected by means of a small spring 36 with a fixed strut 37 extending between the walls 27 and 28 of the enclosure 26 and serves as a toggle spring to maintain the clutch member 33 in either of its extreme positions. A second strut 24' fixed to and extending between the walls 27 and 28, serves as a limit stop for the angular movement of lever 24 in the downward direction, while the yoke 35, by engagement with the tail portion 25 of the lever, serves to limit movement of the latter in the upward direction. For ease in manipulating the clutch the outer end of the rod 34 is provided with a handle in the form of a ring 38.

As will be seen from Figure 3, when the clutch 33 is in its outer or left-hand position, as shown in solid lines, the yoke 35 engages the tail portion 25 of the lever 24, and also the arcuate wall 29 of the enclosure 26, and thus serves as a wedge or block acting between the two, firmly holding the lever 24 against the stud 24', in the position shown in solid lines in Figure 3. Under such circumstances, the lever 24 is rigidly connected to the handle 31, and the windows may be opened and closed by manipulation of the latter. When, however, it is desired to disengage the handle from the operating linkage so that the sash may open to their counterbalanced position and may thereafter be closed by gravity in case of a rainfall, the clutch 33 is moved to its inner or right-hand position, as shown in dotted lines in Figure 3. In this position, the yoke 35 occupies such a position that the lever 24 may swing about the pivot pin 23 into the position shown in broken lines, permitting the sash to open regardless of the position of handle 31. When the sash are closed by gravity, as in the case of a fall of rain, the lever 24 will, of course, return to the position shown in solid lines.

With the clutch in its left-hand or engaged

position, the sash may be locked in any desired attitude by tightening the handle 31 against the spring washer 32 and closure plate 20.

As will readily be understood, opening or closing the sash by means of a simple movement of the handle 31 through a small angle represents a considerable advantage as compared to performing the same operation by the conventional means while at the same time the lever-type operation enables the use of the simple and inexpensive clutch device of the present invention for releasing the sash for gravity or rain operation when desired.

Having thus described the invention, what is claimed as new and desired to be obtained by Letters Patent is:

1. In a window assembly of the type including a plurality of horizontally pivoted sash in vertical series and connected by a common linkage for simultaneous opening and closing movements, a window operating device comprising a supporting frame, a horizontal pivot supported thereon, a lever mounted for vertical angular movement on said pivot, said lever being adapted for connection to said linkage and having a tail portion extending beyond said pivot in the direction away from said linkage, a manually operable member mounted for vertical angular movement about said pivot, and a clutch member mounted for angular movement with said manually operable member and slidably relative thereto into and out of engagement with said tail portion of said lever, said manually operable member comprising a hollow enclosure, and said clutch member comprising a portion which in the engaged position abuts said tail portion on one side and a wall of said enclosure on the other side.

2. A window operator according to claim 1, including resilient means connected as a toggle spring between said clutch member and a wall of said enclosure to yieldingly retain said clutch member in one or the other extreme position.

MATT GZUPKAYTII.
